MOTION PICTURE PROJECTOR

Gregory F. Fossella, Marblehead, Robert G. Palmer, Canton, and Thomas R. Salvo, Stoneham, Mass., assignors to Keystone Mfg. Corp., Boston, Mass., a corporation of Massachusetts

Filed Oct. 21, 1966, Ser. No. 4,366

Term of patent 14 years

(Cl. D61—1)

FIG 1

FIG 2

FIG. 1 is a front perspective view of a motion picture projector showing my new design; and

FIG. 2 is a rear perspective view thereof.

The drawing figures are lined to indicate contrast in appearance.

We claim:

The ornamental design for a motion picture projector, substantially as shown and described.
